UNITED STATES PATENT OFFICE.

WILLEM PETRUS VAN LAMMEREN, OF ROTTERDAM, NETHERLANDS, ASSIGNOR TO U. S. SLICING MACHINE COMPANY, OF LA PORTE, INDIANA, A CORPORATION OF INDIANA.

CLAMP FOR SLICING MACHINES.

Application filed August 16, 1928, Serial No. 129,414, and in Germany June 11, 1925.

This invention relates to clamping devices for holding meat or other material in position to be sliced by the knife of a slicing machine.

The object of the invention is to provide a clamp which shall be of improved construction and convenient and efficient in operation and which will be locked automatically in its position of adjustment.

The invention is exemplified in the combination and arrangement of parts shown in the accompanying drawing and described in the following specification, and it is more particularly pointed out in the appended claims.

15 In the drawings,—

Fig. 1 is an elevation of a clamp embodying one form of the present invention.

Fig. 2 is a top plan view of the clamp shown in Fig. 1.

20 The numerals 10 and 11 designate upright posts, which may project upwardly from points adjacent the front edge of the meat supporting table of the slicing machine. The posts have smooth outer surfaces and are 25 preferably cylindrical, although the cylindrical shape is not essential. Sleeves 12 and 13 are slidably mounted on the posts 10 and 11 respectively and are provided with locking levers 14 and 15 which are pivotally mounted at 16 and 17 on their respective sleeves. A clamping bar 18 is pivoted at 19 to the locking lever 14 and at 20 to a link 21, which is pivotally connected at 22 to the locking lever 15. The sleeve 12 is provided with

30 a handle 23 and the sleeve 13 is provided with a handle 24, the handles being rigid with their respective sleeves. The levers 14 and 15 are each provided with an upper and lower cam face which projects through slots 25 and

35 26 in the respective sleeve 12 and 13 into position to engage the smooth surfaces of the uprights 10 and 11. Springs 27 and 28 normally hold the levers 14 and 15 with their lower bearing faces in contact with the uprights.

40 45 This automatically locks the sleeves from sliding downwardly on their standards 10 and 11, so that the clamping bar 18 is automatically supported in any position to which it is moved upon the uprights. Downward

50 pressure on the handles, however, will move the sleeves 12 and 13 downward for the reason that the pivots 16 and 17 are so close to the posts 10 and 11, respectively, that the pressure on the pivots will cause the lower contacts to slide upon the posts. The pivots

16 and 17 are within the critical angle from the point of contact within which pressure will cause the contacts to slide rather than to bind. In case there should be a tendency to stick, however, it would only be necessary to lift slightly on the bar 18 while the handles are moved downwardly to bring the bar into contact with the work, after which the upward pressure of the work on the bar would prevent the cams from resisting further downward movement. To clamp a piece of meat or other material, it is placed beneath the clamp 18 and the handles 23 and 24 are moved downwardly. As soon as the clamp 18 engages the material it will be held against further downward movement and will raise the pivot points 19 and 22. This will swing the locking levers about their pivots 16 and 17 between the upper locking surfaces into engagement with the standards 10 and 11 so that upon release of the pressure on the handles 23 and 24 the clamp will be automatically locked against upward movement. When it is desired to release the clamp, all that is necessary is to lift upwardly on either or both of the handles 23 and 24, which will raise the pivotal supports 16 or 17 and thus release the clamping lever 14 and will permit the clamp to be lifted. The springs 27 and 28 will hold the clamping levers in position to prevent downward movement and prevent accidental release of the levers from jarring or other disturbance.

I claim:

1. A clamp for holding material to be sliced comprising a clamping member, a support for said clamping member, a lock for automatically holding said clamp against reverse movement when placed into contact with the material to be clamped thereby, and means connecting said clamp with said lock for shifting said lock to its holding position by the upward force exerted on said clamp by the material held thereby.

2. A clamp for holding material to be sliced comprising a support, a clamping element movable vertically on said support, and a lock for holding said clamp for moving downwardly on said support under the action of gravity, the weight of said clamp operating to retain said lock in holding position.

3. A clamp for holding material to be sliced comprising a clamping element, a support on which said element is mounted for

vertical movement, a lock for holding said clamping element against downward movement on said support, said lock being retained by the weight of said clamp in its holding position, and a spring for supplementing the action of the weight of said clamp for retaining said lock in holding position.

4. A clamp for holding material to be sliced comprising a standard, a sleeve mounted to slide on said standard, a locking lever pivotally connected with said lever and having a cam face arranged to engage said standard to hold said sleeve against movement on said standard, and a clamp element attached to said locking lever at a point spaced from its pivotal connection with said sleeve to swing said locking lever on its pivotal connection into engagement with said support when force is exerted on said clamping element.

5. A clamp for holding material to be sliced comprising an upright standard, a sleeve slidably mounted on said standard, a locking lever having two holding portions arranged respectively to hold said sleeve against movement in opposite directions on said standard, and a clamping element connected to said locking lever and arranged to move said lever into position to resist movement of said clamp in either direction.

6. A clamp for holding material to be sliced comprising a standard, a slide mounted on said standard, a lock for holding said slide from movement along said standard, a clamping element connected with said lock and arranged to automatically operate said lock to move said lock into operative engagement with said standard when force is exerted on said clamp to prevent movement of said slide under the influence of said force, and a handle connected with said lock and arranged to release said lock to permit movement of said slide under the influence of force exerted on said handle.

7. A clamp for a slicing machine comprising a standard having a sleeve slidably mounted thereon, a locking lever pivoted on

said sleeve and having contact portions arranged to engage said standard respectively when said lever is moved in opposite directions upon its pivot, a clamping element attached to said lever and arranged to automatically operate said lever to lock said sleeve against movement under the influence of force exerted in either direction on said clamping element, and a handle connected with said sleeve to release automatically said locking lever when force is exerted on said handle to move said sleeve along said standard.

8. A clamp for holding material to be sliced comprising a pair of parallel guide rods, sleeves mounted on said guide rods, locking levers pivotally mounted on said sleeves and having cam faces movable respectively into engagement with said guide rods upon movement of said levers in opposite directions, a clamping bar having one end connected with said levers and arranged to move said levers to lock said sleeves against movement under the influence of force exerted on said clamping bar in either direction, and handles attached to said sleeves for releasing said locking levers when moving said sleeves.

9. A clamp for holding material to be sliced comprising a pair of spaced guide rods, sleeves mounted to slide on said guide rods respectively, locking levers pivotally mounted on said sleeves and having spaced contact portions on the ends thereof adjacent said guide rods, a clamping bar pivotally connected with one of said levers at the end away from said guide rods, a link connecting the opposite end of said clamping bar with the end of the other of said levers away from its guide rod, and handles for moving said sleeves longitudinally along said guide rods.

In testimony whereof I have signed my name to this specification on this 23rd day of July, A. D. 1926.

WILLEM PETRUS van LAMMEREN.
